(57) **CLAIM**

The ornamental design for a crimping tool, as shown and described.

DESCRIPTION

FIG. 1 is a first perspective view of a crimping tool showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 1;

FIG. 11 is an enlarged view of the selected portion 11 in FIG. 1; and,

FIG. 12 is an enlarged view of the selected portion 12 in FIG. 2.

The dash-dash broken lines depict portions of the crimping tool that form no part of the claimed design. The dot-dash broken lines are for the purpose of illustrating the boundary of corresponding views and form no part of the claimed design.

1 Claim, 12 Drawing Sheets
